CLAIM

The ornamental design for an infant car seat and stroller adapter, as shown and described.

DESCRIPTION

FIG. 1 is a perspective view of the infant car seat and stroller adapter;

FIG. 2 is a left side view of the infant car seat and stroller adapter;

FIG. 3 is a right side view of the infant car seat and stroller adapter;

FIG. 4 is a front side view of the infant car seat and stroller adapter;

FIG. 5 is a rear side view of the infant car seat and stroller adapter;

FIG. 6 is a top view of the infant car seat and stroller adapter; and,

FIG. 7 is a bottom view of the infant car seat and stroller adapter.

The broken lines illustrate a connection means between the adapter and stroller, which forms no part of the claimed design.
